Primary Examiner—Mitchell Siegel

(74) Attorney, Agent, or Firm—Harness, Dickey & Pierce, PLC

(57) **CLAIM**

The ornamental appearance of a golf putter head, as shown and described.

DESCRIPTION

FIG. 1 is a perspective view of the golf putter head;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken line showing of the fragmented shaft is for illustrative purposes only and forms no part of the claimed design.
